US00D653105S

(12) **United States Design Patent**
Degeyter et al.

(10) **Patent No.:** **US D653,105 S**
(45) **Date of Patent:** **** Jan. 31, 2012**

(54) **CONTAINER**

(75) Inventors: **Raf Gustaaf Alfons Degeyter**, Donk (BE); **Vincent De Wilde**, Kessel-Lo (BE); **Rainer Scharrenberg**, Kronberg (DE); **Chris Van Den Wouwer**, Mortsel (BE)

(73) Assignee: **The Procter & Gamble company**, Cincinnati, OH (US)

(**) Term: **14 Years**

(21) Appl. No.: **29/380,975**

(22) Filed: **Dec. 14, 2010**

(30) **Foreign Application Priority Data**

Jun. 16, 2010 (EM) 5524333301

(51) **LOC (9) Cl.** **09-03**
(52) **U.S. Cl.** **D9/425; D9/431**
(58) **Field of Classification Search** ..... D9/414, D9/419, 424, 425, 430, 431, 432, 435, 761; D7/538, 549, 550.1, 601–603, 605, 629; 229/105, 117.09, 117.26, 189, 406, 407, 229/902, 905, 915.1; 220/23.4, 23.6, 266, 220/281, 315, 318, 500, 659, 669, 674, 675, 220/696, 75, 2, 760, 790, 793, DIG. 12, FOR. 117; 206/499, 508, 557; D3/276

See application file for complete search history.

U.S. Appl. No. 29/341,570, filed on Aug. 7, 2009, Chris Van Den Wouwer.

Primary Examiner — Thomas Johannes

(74) Attorney, Agent, or Firm — Julie A. McConihay; Leonard W. Lewis; Steven W. Miller

(57) **CLAIM**

The ornamental design for a container, as shown and described.

DESCRIPTION

FIG. 1 is an isometric view of a container, showing our new design;

FIG. 2 is a left elevation view thereof;

FIG. 3 is a right elevation view thereof;

FIG. 4 is a front elevation view thereof;

FIG. 5 is a back elevation view thereof;

FIG. 6 is a top plan view thereof; and,

FIG. 7 is a bottom plan view thereof.

The broken line portion of the figure drawings is included to show unclaimed subject matter only and forms no part of the claimed design.

1 Claim, 3 Drawing Sheets
